UNITED STATES PATENT OFFICE.

ISAAC E. PALMER, OF MIDDLETOWN, CONNECTICUT, ASSIGNOR TO THE I. E. PALMER COMPANY, OF MIDDLETOWN, CONNECTICUT, A CORPORATION OF CONNECTICUT.

HAMMOCK AND SPREADER THEREFOR.

1,120,234.

Specification of Letters Patent.

Patented Dec. 8, 1914.

Application filed April 10, 1914. Serial No. 831,055.

To all whom it may concern:

Be it known that I, ISAAC E. PALMER, a citizen of the United States, and a resident of Middletown, county of Middlesex, State 5 of Connecticut, (whose post-office address is Middletown, Connecticut,) have invented an Improvement in Hammocks and Spreaders Therefor, of which the following description, in connection with the accompanying drawings, is a specification, 10 like characters on the drawings representing like parts.

This invention relates to hammocks and to spreaders therefor, an important object 15 of the invention being to provide a hammock which can be packed in small compass for storage or transportation.

In order that the principle of the invention may be readily understood, I have dis- 20 closed a single embodiment thereof in the accompanying drawing, wherein—

Figure 1 is a plan view of a hammock embodying my invention; Fig. 2 is a trans- 25 verse section taken through the head end of the hammock at the spreader pocket; Fig. 3 is a similar view at the foot end of the hammock; and Fig. 4 is a view similar to Fig. 1, but representing two of the members of the spreader as disconnected.

30 An important object of this invention is to provide a hammock peculiarly adapted for sportsmen, campers or others moving from place to place.

The hammock of my invention is com- 35 posed of a suitable body portion 1 of woven or other material and may if desired be provided with integral or attached edge balances. At the head end of the hammock I provide a pillow receiving pocket 2, 40 which is preferably attached to the ham- mock body along its upper and lower edges, as indicated at 3, 4, and is provided with an open end or ends 5, 6 for insertion and ready removal of the head pillow. If de- 45 sired, the pocket may be woven or other- wise integrally formed with the body of the hammock, but I prefer to provide a separate piece sewed or otherwise secured thereto. Intermediate the ends of the ham- 50 mock, and preferably about midlength thereof, I provide a similar pocket 7 attached to the body at its upper and lower edges 8, 9, and having a free end or ends 9', 10. Within the pocket 7 I may posi- 55 tion a body receiving pillow. The said

pillows may be of any suitable length, but preferably are not substantially longer than the length of the pockets. Upon removal of the pillow or pillows the hammock may be readily rolled or folded into small compass. 60

At one or both ends of the hammock, I provide a sectional spreader of improved form, the members thereof being adapted to be readily and wholly disconnected, or 65 to be united or assembled into substantially rigid form.

Hammocks have heretofore been pro- 70 vided with sectional spreaders, as shown for example, in my prior Patents, No. 700,978, May 27, 1902, and No. 964,452, July 2, 1910, and also as shown in the patent to Funke, No. 518,568, April 17, 1894. In these structures, however, the members 75 of the spreader are not adapted to be wholly disconnected, nor are they adapted to be attached together in substantially rigid form.

In that form of my invention herein shown, I provide at the head end of the 80 hammock a pocket 11 consisting of a plurality of divisions, herein three in number, 12, 13 and 14. Obviously, however, any suitable number of such divisions may be em- 85 ployed. As shown most clearly in Figs. 2 and 4, each division of the pocket is pro- 90 vided with hemmed or other suitable edges 15, preferably spaced sufficiently apart, as indicated in said figures, to expose the meeting ends of the sectional spreader. I pro- 95 vide a spreader consisting of a plurality of members, the number thereof corresponding to the number of divisions of the spreader pocket. Herein I have represented at the head end of the hammock three spreader 100 members 16, 17 and 18 preferably formed of wood. In the preferred embodiment of my invention, I provide the meeting ends of the said spreader members with sleeve or socket means. For this purpose I have here- 105 in represented the intermediate spreader 17 as having secured to each end metallic sockets or sleeves 19, 20 of sufficient length to receive the adjacent spreader ends and to hold them in rigid relation. I have herein re- 110 presented said sleeves as secured to the spreader member 17 by pins 21.

The spreader members may be readily disconnected by grasping the adjacent pocket divisions and stretching them slightly apart, 115

thus permitting the separation of the spreader members, as indicated at the left in Fig. 4. The spreader members can be as readily restored to rigid relation with respect to each other. When the spreader members are separated, they can be folded against each other, and the whole hammock readily packed for storage or transportation. At the foot end of the hammock I provide a spreader pocket 22 adapted to receive a sectional spreader composed of any suitable number of members, but preferably two, as indicated at 23, 24 in Fig. 3. In this case, I provide one of said spreader members with a sleeve 24 secured thereto by a pin 25 and adapted to receive the adjacent end of the spreader member 23, as already described. Preferably also the spreader pocket 22 is composed of a pair of corresponding number of divisions 26, 27 as described with reference to the head end of the hammock.

I provide suitable suspension means at the ends of the hammock. For that purpose I have herein represented clew cords 28, 29 suitably connected to suspension rings 30, 31. The said clew cords are attached to the respective divisions of the pockets 11 and 22, and if desired the clew cords may be continuous, extending from one point of connection at the pocket to another, and thus spanning, if desired, the divisions thereof, as indicated in Fig. 1.

It will be clearly evident from the foregoing description that the hammock is peculiarly adapted to be packed in small compass, so that it may be readily transported from place to place by campers, sportsmen or others.

Having thus described one illustrative embodiment of my invention, I desire it to be understood that although specific terms are employed, they are used in a generic and

descriptive sense and not for purposes of limitation, the scope of the invention being set forth in the following claims.

Claims.

1. A hammock having a transverse pocket and a spreader therein consisting of a plurality of members adapted to be wholly and readily disconnected, and means for attaching them together in substantially rigid relation.

2. A hammock having at an end thereof a transverse pocket consisting of a plurality of divisions, and a spreader positioned in said pocket and consisting of a corresponding plurality of members adapted to be wholly and readily disconnected at the divisions of said pocket without removal therefrom, and means for attaching said members together in substantially rigid relation.

3. A hammock having at an end thereof a transverse pocket consisting of a plurality of divisions slightly spaced apart, and a spreader positioned in said pocket and consisting of a corresponding plurality of members having ends adapted to protrude from said divisions, and sleeve means for attaching said members together in substantially rigid relation.

4. A hammock having at an end thereof, a transverse pocket and a sectional spreader therein consisting of a series of readily detachable members socketed together.

5. A hammock having at an end thereof, a transverse pocket and a spreader therein consisting of a series of detachable members sleeved together.

In testimony whereof, I have signed my name to this specification, in the presence of two subscribing witnesses.

ISAAC E. PALMER.
